UNITED STATES PATENT OFFICE

2,311,804

CURVOMETER

Arthur J. Wright, Dallas, Tex.

Application October 12, 1942, Serial No. 461,829

6 Claims. (Cl. 33—175)

This invention relates to apparatus for gauging curved bodies and more particularly to a curvometer especially adapted for determining the concave and convex surfaces of lens grinding laps.

The principal object of the invention is to provide a curvometer wherein is provided a plurality of cams, mounted on a common shaft, each bearing the same radius circle and predeterminedly spaced apart and arranged on said shaft so that the lines of each right angle design of the cams are respectively parallel. Moreover, the invention provides for the setting of the cams through the medium of a manually actuated dial, suitably calibrated for minute setting and after having been set, the cams afford stops for an equal number of spring controlled, longitudinally movable prongs or fingers, whose movement into contact with the peripheries of the cams is effected by the work itself in the process of defining the curve thereon which is accomplished when the curve of the work corresponds to the curve presented by the terminals of the fingers collectively.

Another object of the invention is to provide a curvometer with which curved surfaces are gauged by fingers actuated by the work and restricted in these movements by cams serving as templets and further, the provision of electrical means which will visibly disclose whether or not the curve of the work to be gauged corresponds with that defined by the terminals of the fingers.

Broadly, the invention seeks to provide an apparatus of the character specified by which regular or irregular curves, both concave and convex, may be gauged with greater precision and accuracy than is possible by fixed gauges where accuracy, to a considerable extent, depends upon the care and skill exercised by a workman in applying them.

With the foregoing objects as paramount, the invention has particular reference to certain features of accomplishment, to become manifest as the description proceeds, taken in connection with the accompanying drawings, wherein:

Figure 1 is a perspective view of a curvometer embodying the principles of the present invention.

Figure 2 is a plan view, partly broken away.

Figure 3 is a diagrammatic plan view of the cam and finger assembly and electrical system associated therewith.

Figure 4 is a plot of the physical movements of the plus cam assembly.

Figure 5 is a detail view of the central or number one cam.

Figure 6 is a detail view of an intermediate or number two cam.

Figure 7 is a detail view of the outside or number three cam.

Figure 8 is a detail view of the central cam of the minus cam assembly.

Figure 9 is a detail view of an intermediate or number two minus cam.

Figure 10 is a fragmentary plan view of one of the minus system fingers, and

Figure 11 is a side elevational view thereof.

Continuing with a more detailed description 15 of the drawings, reference is primarily made to Figures 1 and 2 showing respectively a perspective and plan view of the machine and wherein 10 designates a frame supported upon legs 11 and upon which is disposed a ferrous plate 12. 20 It may be mentioned at this point that the plate 12 may be constructed of plastic or other non-conducting material so long as provision is made for completing a circuit through the electrical system for the purpose to be hereinafter described.

In the approximate center of the plate 12 there is provided an opening 13 to accommodate the cam assembly, to be presently described, and its associated elements. On each side of this 30 opening is situated a pillow block 14, affording bearings for the shaft 15. The shaft 15 carries a large gear 16 on one end, a portion of which is received in a slot 17 in the plate 12 and whose teeth enmesh those of a small gear 18, mounted 35 on a stub shaft 19, which operates in bearings 20.

Mounted on the stub shaft 19 is a calibrated dial 21, the numerical graduations 22 on which may be of any nature suited to the character of the work whose curves are to be gauged. In 40 the present case, however, and as an example of the several adaptations of the machine, the dial 21 has been marked with dioptric units according to the metric system used in optometry in measuring the accommodation and refraction 45 of the eye. While the division of the dial markings is arbitrary, it is preferred that the calibrations be so spaced that each mark will represent a .03D change and in order that the markings will be clearly legible, a magnifying glass 23

50 is mounted in a frame 24 overlying one point on the dial 21 and supported from the plate 12 on a leg 25. A hair line 26 on the glass serves as a marker for the graduations of the dial. 55 In Figures 4 to 7, inclusive, is shown the plus system of cams and while specific dimensions

are shown for a comprehensive understanding of one application of the invention, no limitation is intended. The cams are indicated on the drawings as 26, denoting the central or number one cam 27, denoting the intermediate or number two cam and 28, denoting the outside or number three cam. In these dimensions, angle arcs ABC—A'B'C—A²B²C have a radius of 33.65 mm. Point D is the center line of shaft 15 and the external face of arcs AC—A'C—A²C is the measuring plane for the plus system of cams.

The cams 26, 27, and 28 are arranged on the shaft 15 in the manner particularly shown in Figures 1 and 2, that is, with cam 26 or number one centrally disposed and flanked by cams 27 and 28, the cams 27 occupying intermediate positions between cam number one and the outside cams 28.

The cams are fixed on the shaft 15 so that the lines of each right angle design of the cams are respectively parallel and are limited to an arcuate movement of 90°. Such movement of the cams is, of course, affected by moving the dial wheel 21 and the degree of rotation is determined by the ratio of the gears 16 and 18, which, of course, depends upon the character of work to be measured and other factors including the size and spacing of the cams. Moreover, the cams are so disposed in relation to the dial that when they are positioned for a zero reading, the dial is at its zero mark.

Mounted for longitudinal sliding movement in guides 29 is a series of fingers 30, corresponding in number to the cams and which pass between and alongside the cams, above the surface of plate 12. Springs 31, disposed underneath the fingers, are connected to points on the fingers spaced from the foremost guide 29 and to the guide itself and serve to resist inward thrust of the fingers. As a stop and means for predetermining the outward movement of each finger, nuts 32 are threaded upon the rearmost threaded ends of the fingers and bear against the rearmost guide 29.

Attending each finger 30 is a contact prong 33 which is made rigid with its finger by an insulator mounting 34, the latter being secured to the finger by a set screw 35. In the present adaptation of the invention, the prongs 33 are spaced 12 mm. apart horizontally, each also being spaced vertically in respect to the different plane of action of the cams, that is to say, these planes of action remain in elevation 6 mm. apart. The tips of each prong 33 is spaced horizontally along the finger 30 with respect to the zero point on the cam faces. For example, the number two cams 27 have their zero reading points on their face 6 mm. horizontally behind the respective reading point on the number one cam 26 and the number three cams 28 have their zero reading points 6 mm. horizontally behind the respective points on the number two cams 27. This horizontal spacing of the prongs 33 along the cams is arranged with the finger tips 46 and 48 on a true parallel.

To each prong 33, there is connected a wire 36 (Figure 3) which wires extend to signal means, which, in the present case, consist of incandescent lamps 37. The lamps 37 are, in turn, connected to the supply wires 38 through wires 39 and a transformer 40. Ground is established from one leg of the transformer 40, through wire 41 to the plate 12. As stated previously, should it be desired to construct the plate 12 of plastic

or other non-conducting material, other suitable types of ground may be adapted.

In the grinding and polishing of eyeglass lenses, concave laps are used for producing a plus curve on a lens blank, while convex laps are employed where minus curves are desired. Figures 1 to 7 illustrate the adaptation of a system wherein plus curves are gauged while Figures 8 and 9 illustrate cams 43 and 44, used in the minus system. The internal face of arcs AC—A'C—A²C is the measuring plane for the minus system of cams. Therefore, the plot of physical movement for plus-minus systems is the same. However, the number three minus cam 44 (Figure 9) are fastened to a collar 45 in a half circle, as shown, so that the maximum clearance can be obtained for the fingers or prongs, whose relationship with the minus cams is the same as in the plus system of cams.

In operation, if a plus lap having a 7.00 curve is to be identified or measured, the dial 21 is rotated until this unit is aligned with the hair line 26. The cams 26, 27, and 28 are thus brought into a corresponding position so that when the lap to be gauged is urged against the tips of the fingers 30, they will be longitudinally actuated against the tension of springs 31 toward the cams, bringing the prongs 33 into contact with the surfaces of the cams. Thus, the cams perform in the capacity of templets and their relative positions determine the curve defined by the ends of the fingers 30 which will be precisely 7.00, corresponding to the marking on the dial 21. In the event the curve of the lap is exactly 7.00, then circuits will be completed through all of the lamps 37 by means of all of the contact prongs 33, wires 36 and cams, the latter through the ground wire 41, plate 12 and shaft 15. On the other hand, a deeper curve on the lap would succeed in illuminating only the end lamps while a shallower curve will effect illumination of the central lamp through the central or number one cam.

In measuring a plus lap or curve, the tips of the fingers 30 are provided with balls 46 so that there will be no differential error caused by deviation of contact between the axes of the fingers and the surface to be gauged. For the same reason, the fingers 47 (Figures 10 and 11) are provided with flat tips 48. These latter fingers are designed to operate with the minus cam system and the function of this system is the same as in the plus system.

It is apparent from the foregoing that a high degree of accuracy and assurance thereof is obtainable through the use of the invention and where conventional metal gauges with fixed curves are employed to measure laps, not only do human errors reduce the possibility that a high degree of accuracy will be had in all cases, but also, where precision is required within .03 of a diopter for some lenses, fixed curve gauges frequently result in error by reason of worn or damaged surfaces, or by bits of foreign matter between the gauge and the work.

It is understood that irregular as well as regular curves can be as accurately gauged by utilizing the same principle as hereinabove described. To thus adapt the machine, a rearrangement of the cams to present the required surfaces to the fingers and prongs will, of course, be necessary.

Manifestly, the construction as shown and described is capable of some modification and such modification as may be construed to fall within the scope and meaning of the appended claims

is also considered to be within the spirit and intent of the invention.

What is claimed is:

1. An apparatus for gauging curved bodies including a plurality of predeterminedly spaced cams fixed on a shaft and having substantially the same radius circle, a calibrated dial also fixed on said shaft, whose rotation predeterminedly the angular positioning of said cams and whose calibrations correspond to and denote the pattern collectively produced thereby, a plurality of longitudinally movable fingers of equal length in operative relation to said cams, an electrically energizable prong carried by each of said fingers, said prongs being predeterminedly spaced relative to each other and to the faces of respective cams whereby said fingers, when actuated, will be limited in their movement by contact of said prongs with the faces of said cams to define at their ends a curve pattern corresponding to that collectively produced by said cams and visibly disclosed on said dial and signal means visibly revealing correlation between the curve of said pattern and that of a body.

2. An apparatus for gauging curved work surfaces, a cam assembly fixed on a shaft and a series of fingers corresponding in number to the cams, constrained to move longitudinally, means mounted on said fingers and engageable with the surfaces of said cams, which latter limits the displacement of said fingers and predeterminedly the curve pattern defined by the ends thereof in relation to the position of said cam assembly, a dial calibrated to denote the potential curve pattern of said cam assembly when a work surface is impressed on the ends of said fingers and electrical signal means common to each cam for revealing the curve differential between said work surface and that defined by the ends of said fingers.

3. In an apparatus for gauging curved work, a cam assembly mounted for rotation in an arc of substantially 90°, each cam of said assembly bearing the same radius circle and in which the lines of each right angle design are respectively parallel, means for actuating and visibly indicating the variations in pitch of said cam assembly to denote a distinctive curve, means actuated by the work and controlled by the cams of said assem-

bly for developing a curve pattern by known equations, means for setting said cam assembly preparatory to developing said curve and means common to each cam of the assembly for electrically indicating the curve differential between that of the work and the developed patterns.

4. A curvometer including an assembly of cams consisting of segments of a circle and aligned in equidistantly spaced relation on a shaft to serve as templates, means for moving said cams simultaneously in an arc to vary the potential curve pattern thereof and having means thereon to denote a selected curve, a series of longitudinally movable members against the ends of which a work piece is pressed, said members being under spring tension to constrain the same to become oriented to the curve of the work, electrically energizable means carried by each of said members and engageable with the faces of said cams to visibly indicate the same or a different curve from that of said work.

5. A curvometer including a series of relatively parallel and coextensive members constrained under spring tension to move longitudinally when a work piece is urged against the ends thereof, an assembly of templates movable arcuately on a common axis and collectively presenting a potential curve pattern through a predetermined range of equations, electrically energizable means carried by and insulated from said members and engageable with said templates individually when said members are actuated to transfer to said members the curve pattern presented by said templates and means connected electrically with said energizable means for visibly indicating the corresponding or curve differential between that of said work and the pattern of said templates.

6. An apparatus as set forth in claim 5 in which the electrically energizable means are predeterminedly spaced apart in two planes relative to each other and to the templates, the said spacing corresponding to the fixed profile of the templates to insure predetermined orientation of the longitudinally movable members and means to effect adjustment of the longitudinal displacement of said members.

ARTHUR J. WRIGHT.
